Primary Examiner — George D. Kirschbaum

Assistant Examiner — Maria J Edwards

CLAIM

I claim the ornamental design for a headboard cover, as shown and described.

DESCRIPTION

FIG. 1 is a front view of a headboard cover showing my new design.

FIG. 2 is a right side view thereof, the left side being a mirror image of the right side.

FIG. 3 is a top view thereof.

FIG. 4 is a bottom view thereof; and,

FIG. 5 is a perspective view thereof, as it appears on a bed frame.

The broken lines on FIG. 1 and FIG. 5 of balls are environmental matter forming no part of the claimed design. The broken lines on FIG. 5 of a bedframe are environmental matter forming no part of the claimed design.

1 Claim, 4 Drawing Sheets
